DESIGN FOR A TOY ARTICLE-DISPENSING DEVICE

Jacob Markoe, Brooklyn, N. Y., assignor to Select Jewelry Mfg. Co. Inc., Long Island City, N. Y., a corporation of New York

Application May 1, 1948, Serial No. 146,110

Term of patent 7 years

(Cl. D52—3)

To all whom it may concern:

Be it known that I, Jacob Markoe, a citizen of the United States and a resident of Brooklyn, county of Kings, and State of New York, have invented a new, original, and ornamental Design for a Toy Article-Dispensing Device, of which the following is a specification, reference being had to the accompanying drawing, forming part thereof.

Fig. 1 is a front elevational view of a toy article-dispensing device embodying my new design;

Fig. 2 is a rear elevational view of the same;
Fig. 3 is a top view; and Figs. 4 and 5 are side elevational views taken respectively from the right and left sides of Fig. 1.

I claim:

The ornamental design for a toy article-dispensing device, substantially as shown.

JACOB MARKOE.
